Primary Examiner — Elizabeth J Oswecki(74) *Attorney, Agent, or Firm* — Taylor English Duma LLP(57) **CLAIM**

The ornamental design for a removable golf spike cleat body, as shown and described.

DESCRIPTION

FIG. 1 is a perspective view of a removable golf spike cleat body showing my new design;

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines shown in the drawings represent portions of the removable golf spike cleat body that form no part of the claimed design.

1 Claim, 5 Drawing Sheets
